(57) **CLAIM**

The ornamental design for a portion of an embossed shelf edge in shelf unit, as shown and described.

DESCRIPTION

FIG. 1 is an isometric view of a portion of an embossed shelf edge unit;

FIG. 2 is an enlarged perspective view of a portion of the shelf edge of FIG. 1;

FIG. 3 is a front view of the design of FIG. 1;

FIG. 4 is a right side view of the design of FIG. 3;

FIG. 5 is a rear view of the design of FIG. 3;

FIG. 6 is a left side view of the design of FIG. 5;

FIG. 7 is a top view of the design of FIG. 2; and,

FIG. 8 is a bottom view of the design of FIG. 7.

The broken lines shown in FIG. 1 form no part of the claimed design.

The break lines shown at the edges of the claimed design indicate a non-specified length and form no part of the claimed design. It is understood that the embossed pattern repeats uniformly across the surface to which it is applied.
